United States Patent Office

Des. 231,327

Patented Apr. 16, 1974

231,327

REEL

Orion L. Schultz, 7559 Locklin,
Union Lake, Mich. 48085

Filed Jan. 5, 1973, Ser. No. 321,246

Term of patent 14 years

Int. Cl. D8—08, 06; D22—05
U.S. Cl. D8—220

FIG. 1 is a perspective view of the reel of my new design;

FIG. 2 is a top view of the reel shown in FIG. 1;

FIG. 3 is an end view as seen from the left side of FIG. 2;

FIG. 4 is a view as seen from the bottom of FIG. 2; and

FIG. 5 is a view as seen from the bottom of FIG. 4.

I claim:

The ornamental design for a reel, as shown.
